[57] CLAIM

The ornamental design for a truck, as shown and described.

DESCRIPTION

FIG. 1 is a front and side perspective view of a truck showing our new design;

FIG. 2 is a rear and side perspective view thereof;

FIG. 3 is a front view thereof;

FIG. 4 is a rear view thereof;

FIG. 5 is a top view thereof; and,

FIG. 6 is a right side view thereof, the left side being a mirror image.

The bottom view is omitted since we do not regard it as part of our claimed design.
